(57) **CLAIM**

The ornamental design for the seating shell, as shown.

DESCRIPTION

FIG. 1 is a top perspective view of a seating shell embodying the present invention;
FIG. 2 is a front perspective view of the seating shell;
FIG. 3 is a rear elevational view of the seating shell;
FIG. 4 is a rear perspective view of the seating shell;
FIG. 5 is a front elevational view of the seating shell;
FIG. 6 is a first side elevational view of the seating shell;
FIG. 7 is a second side elevational view of the seating shell;
FIG. 8 is a top plan view of the seating shell; and,
FIG. 9 is a bottom plan view of the seating shell.
